UNITED STATES PATENT OFFICE.

ROBERT BOETTLER, OF CLEVELAND, OHIO.

SPRING DRAFT ATTACHMENT.

SPECIFICATION forming part of Letters Patent No. 482,504, dated September 18, 1892.

Application filed May 31, 1892. Serial No. 435,089. (No model.)

To all whom it may concern:

Be it known that I, ROBERT BOETTLER, a citizen of the United States, and a resident of Cleveland, in the county of Cuyahoga and 5 State of Ohio, have invented certain new and useful Improvements in Spring Tug Attachments for Thills, of which the following is a specification.

This invention relates to a spring attachment for harness-tugs to a wagon or vehicle thills, having for its objects to dispense with the whiffletree and to relieve the jar upon the horse.

The invention consists in the construction 15 and combination substantially as hereinafter described, and pointed out in the claim.

In the accompanying drawings, Figure 1 represents a pair of thills having my invention attached. Fig. 2 is an enlarged detached 20 perspective view of my new spring tug attachment.

A is the cross-bar of a pair of thills, to which is usually attached a whiffletree, which I have discarded and provided instead the 25 spring tug attachments, as shown.

B represents a folded spring, one fold of which is secured to the rear side of the cross-bar A next to the thills by means of bolts or other suitable means.

30 C is a yoke which embraces the cross-bar

A and is pivotally attached to the free or moving end of said springs, the ends of the yoke being provided with eyes and the end of the spring with a tubular fold or long eye, through which a bolt is put for pivotally uniting them. The forward or bow end of the yoke is provided with a hook D, having its point standing upright, upon which the loop or eye of a harness-tug is readily and easily placed or removed.

From the description and drawings it will be readily seen that this makes an easy and comfortable tug attachment, economical and durable, and which relieves the horse of jerking and jarring in starting or hauling.

Having described my invention, I claim—
A spring tug attachment for thills, consisting of U-shaped springs B B, one arm of each spring secured to rear side of cross-bar A of the thills, and U-shaped yokes C C, embracing 50 said cross-arm and pivotally attached to the free ends of the springs B B and provided with hooks D D, whose points stand upright, substantially as described, and for the purpose set forth.

ROBERT BOETTLER.
